[57] CLAIM

The ornamental design for a detachable flashlight mount for firearms or similar article, as shown and described.

DESCRIPTION

FIG. 1 is a top, front, left side perspective view of a detachable flashlight mount for firearms or similar article showing my new design;

FIG. 2 is a left side elevational view thereof, the right side being a mirror image;

FIG. 3 is a front elevational view thereof, the rear being a mirror image;

FIG. 4 is a top plan view thereof;

FIG. 5 is a bottom plan view thereof.

The flashlight and gun are shown in broken lines in FIG. 2 for illustrative purposes only.

FIG. 1

FIG. 2

FIG. 3

FIG. 4

FIG. 5
